UNITED STATES PATENT OFFICE

168,808

EXPANSIBLE BRACELET

Saul Ritter, New York, N. Y., assignor of one-half
to Marvin J. Bruner, New York, N. Y.

Application January 12, 1951, Serial No. 13,781

Term of patent 7 years

(Cl. D45—4)

To all whom it may concern:

Be it known that I, Saul Ritter, a citizen of the United States, residing at 927 Fifth Avenue, New York city, in the county of New York and State of New York, have invented a new, original, and ornamental Design for an Expansible Bracelet, of which the following is a specification, reference being had to the accompanying drawing, forming part thereof.

Fig. 1 is a top plan view of an expansible bracelet showing my design, the narrower links continuing to the conventional end connectors as illustrated by the broken lines;

Fig. 2 is an edge view taken from the top of the bracelet as shown in Fig. 1;

Fig. 3 is a bottom plan view of that portion of the bracelet shown in full lines in Figs. 1 and 2; and

Fig. 4 is a top plan view illustrating that portion of the bracelet shown in full lines in Figs. 1 and 2 in an expanded position.

The dominant feature of my design for an expansible bracelet resides in the relatively wide,

flat surface areas of the several center links in association with the narrower surface areas of the flanking links.

I claim:

The ornamental design for an expansible bracelet, as shown and described.

SAUL RITTER.
